(57) **CLAIM**

The ornamental design for a surface configuration of a knife handle, as shown and described.

DESCRIPTION

FIG. 1 is a right side elevational view of a surface configuration of a knife handle showing my new design; the left side being a mirror image thereof;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a top left perspective view of FIG. 1.

The broken lines are for illustrative purposes only and form no part of the claimed design.

1 Claim, 2 Drawing Sheets

FIG. 5

FIG. 6
